UNITED STATES PATENT OFFICE.

RICHARD C. ROSE, OF OSCEOLA, ARKANSAS.

INDUCTION COIL MOUNTING.

Application filed August 27, 1923. Serial No. 659,591.

To all whom it may concern:

Be it known that I, RICHARD C. ROSE, a citizen of the United States, residing at Osceola, in the county of Mississippi and State of Arkansas, have invented a new and useful Induction Coil Mounting, of which the following is a specification.

This invention has reference to inductance coil mountings especially designed for use in radio receiving systems, the primary object of the invention being to provide a device of this character wherein the mutual inductance between the primary and secondary circuits may be varied uniformly throughout the entire areas of the coils.

Another object of the invention is to provide a device of this character which may be used for either double or triple mounts for practically any conventional type of coils, means being provided to permit of minute adjustment of the mutual inductive fields.

Another important object of the invention is to provide a coiled mounting constructed for the reception of coils of various sizes, thereby adapting the device for various usages.

With the foregoing and other objects in view which will appear as the description proceeds, the invention resides in the combination and arrangement of parts and in the details of construction herein-after described and claimed, it being understood that changes in the precise embodiment of the invention herein disclosed, may be made within the scope of what is claimed, without departing from the spirit of the invention.

Referring to the drawings:

Figure 1 is an elevational view disclosing the mount constructed in accordance with the invention.

Figure 2 is a sectional view taken on line 2-2 of Figure 1.

Figure 3 is a fragmental elevational view of the panel.

Figure 4 is a side elevational view of the device disclosing the same as supporting a plurality of coils.

Figure 5 is a sectional view taken on line 5-5 of Figure 4.

Figure 6 is a sectional view taken on line 6-6 of Figure 4.

Figure 7 is a sectional view taken on line 7-7 of Figure 1.

Figure 8 is a sectional view taken on line 8-8 of Figure 1.

Figure 9 is a sectional view illustrating the connection between the coil and contact member associated therewith.

Referring to the drawings in detail, the reference character 5 designates a portion of a panel of a radio apparatus, on which the mounting is positioned.

Extending from the panel 5 is a supporting member 6 formed of suitable insulating material which supporting member is held in an upright position by means of the angle plate 7. Secured to the plate 7 are the clamping blocks 8 which are disposed in suitable spaced relation with each other to receive the extension 9 of the spider web coil 10.

Arranged on opposite sides of the clamping blocks 8 are spring arms 11 which are formed with depressions 12 at points adjacent to their upper ends, which depressions receive the contact members 13 carried by the inductance coil, whereby the circuit through the wires of the inductance coils will be completed to the arms 11 which are in circuit with the necessary leading-out wires. From the foregoing it will be seen that due to this construction the central inductance coil is held in a stationary position. The reference character 14 indicates bearing members which are secured to the supporting member 6 at a point adjacent to the upper end thereof, which bearing members provide bearings for the operating rods 15 that have right angled extremities 16 to which are secured the fingers 17, the opposite ends of the rods extending through the panel member 5 where they are supplied with operating knobs 18 that are supplied with dials 19 whereby the degree of rotation of the dials and movements of the arms may be accurately registered.

Secured to the panel 5 at opposite sides of the coil 10 are binding posts indicated at 20, which binding posts are formed with bearings 21 in which the extensions 22 of the coil supporting frames 23 move to permit of rocking movement of the frames 23 and coils supported therein. As shown, the lower extremities of the arms of the frames 23 are secured to the insulating bars 24, thereby allowing the electric energy to pass through the arms of the frames 23 to the coils supported thereby. The coils sup-

ported by the frames are indicated at 25 and have bearings 26' that connect the coils to the frames in a manner to permit of pivotal movement of the coils within its frames.

5 An operating bar 26 is pivotally supported on each panel 5 at 27, and is formed with an opening 28 to receive the finger 17 associated therewith, whereby with movement of the finger and rod supporting the same, a 10 relative movement of the operating bar 26 will be had. The upper end of the operating bar 26 has connection with the bearing member 26' of the frame 25 associated therewith, by means of the bar 29 so that movement of the bar 26 is transmitted to the frame for moving the frame and coils supported thereby towards and away from the coil 10 to vary the inductance of the coils.

15 Due to the connection between the bar 29 and bearing 26' it will be obvious that as the arm 29 moves downwardly and the frame 23 is moved away from the coil 10, the frame 23 will swing downwardly and the frames 25 will be swung on their pivots in 20 such a way as to hold them in parallel relation with the coil 10.

25 While I have shown and described a triple mount, it is to be understood that one of the coils may be removed and the device used as 30 a double mount.

35 From the foregoing it will be obvious that as the operating knobs 18 are moved, the frames which are indirectly operated thereby, are moved towards and away from the central inductance coil, to the end that the mutual inductance between the primary and secondary circuits is varied uniformly throughout the entire areas of the coils.

40 The foregoing result is accomplished by the pivotal connection between the frame 23 and coil supported thereby insuring the movable coils being held at all times in a plane parallel to the fixed coil.

I claim:—

45 1. An inductance coil mounting comprising a panel, means for removably mounting a stationary coil on the panel, pivoted frames mounted on the panel, coils disposed in the pivoted frames, and means for moving the 50 pivoted frames and coils supported thereby to cause the coils of the pivoted frames to move in parallel relation with the stationary coil.

55 2. An inductance coil mounting comprising a panel, a stationary coil mounted on

the panel, pivoted frames movable on opposite sides of the stationary coil, pivoted coil supporting members mounted in the frames, and means for operating the pivoted frames and pivoted coil supporting members to cause the coils supported therein to move in parallel relation with the stationary coil.

3. An inductance coil mounting including a panel, a supporting member extending from the panel, a pair of spring arms disposed adjacent to the supporting member and secured to the panel, a stationary coil including laterally extending contact points adapted to engage the spring arms, to support the stationary coil against movement, pivoted frames operating on opposite sides of the stationary coil, pivoted frames mounted in the pivoted frame, coils mounted on the pivoted frames and means for operating the frames to cause the pivoted coils supported thereby to move in parallel relation with the stationary coil.

4. An inductance coil mounting comprising a panel, a supporting member on the panel, bearings on the supporting member, operating rods having right angled ends disposed in the bearings, fingers carried by the right angled ends of the rods, a stationary inductance coil mounted on the panel, movable frames disposed on opposite sides of the stationary coil, pivoted coil frames mounted in the movable frames, operating arms for the frames, said operating arms having openings to accommodate the fingers, and said pivoted frames adapted to be moved by the operating arms to move the coils supported by the coil frames in parallel relation with the stationary coil.

5. An inductance coil mounting comprising a panel, a stationary coil supported by the panel, bearing members on the panel, pivoted frames supported in the bearing members, pivoted coil supporting frames supported in the first mentioned frames, and means for operating the pivoted frames to cause the coils supported thereby to move in parallel relation with the stationary coils.

In testimony that I claim the foregoing as my own, I have hereto affixed my signature in the presence of two witnesses

RICHARD C. ROSE.
